LOOM

Application filed October 3, 1928. Serial No. 310,162.

This invention relates to looms of the class in which the filling is carried through the warp sheds by a device which enters the sheds from one side thereof and returns, leaving a loop in the shed to form a "pick" or "shot" thereof, and especially looms of this class in which provision is made for passing a binder thread through each loop as it is formed.

10 I have devised a loom of this type (parts and combinations of parts of which I have set forth in other co-pending applications hereinafter identified) which is very simple in construction, requires but indifferent skill 15 to operate and keep it in proper working order and may be driven at very high speed and yet produce an excellent fabric. These qualities are largely due to certain novel combinations having to do with the actual installation, as intended, of those threads which 20 with the warp go to compose the fabric, such being the subject of the present application.

In the drawings,

Fig. 1 is a side elevation of sufficient of 25 a loom embodying the invention to illustrate the same;

Fig. 2 is a plan of the principal parts of the invention;

Fig. 3 shows in front elevation, partly in 30 section, the means for operating the binder-thread shuttle or carrier; and

Fig. 4 is a longitudinal sectional view of such shuttle or carrier.

The warp A and fabric B is assumed to be 35 supported and held in the condition of a stretched sheet by any suitable means, of which the rollers 1 and 2 may form parts. 3 denotes means for forming sheds in the warp. 4 is the loom frame.

40 On a part of the frame is oscillatory, with its axis of oscillation vertical and beyond the sheet (Fig. 2), what I term a looper, or more broadly a filling feeder, which here comprises the axial portion 5 below the plane of the 45 sheet A-B, the radial portion 6 and the curved portion 7 whose extremity has a guide 7^a, as an eye, for the filling C and lies for the most part approximately in the plane of the sheet. Its range of oscillation is such that 50 when it is retracted guide 7^a is at the near

side of, and the looper tip points toward, the sheet and when it is forward the looper extends through the shed then already formed by the means 3. As in my application Ser. No. 310,160, the looper extremity is preferably curved and in its convex side it has a groove 7^b in which, subject to the cooperation of the guide 8 (Fig. 2), when the looper is more or less out of its fully retracted position the portion of the filling between guides 7^a and 8 reposes, thus to maintain the loop in a definite and steady condition.

The device for beating up the loops of filling as they are formed and deposited in the sheds is a structure 9 supported in proximity to the fell-line B' of the fabric. In the example it is dentate in form and supported by being fulcrumed at 9^a, with its fulcrum axis close to the sheet and parallel with the fell-line. It should when fulcrumed be formed so that when retracted the looper may pass without interference therewith and so that its dents will remain intermeshing with the warp threads to avoid their wearing and perhaps breaking them in entering into the intermeshing relation each time the beating-up movement occurs. Hence the dents are formed so that when said device is in retracted position they extend generally lengthwise of said sheet except for their end portions, which are bent off in the beating-up 75 direction and in that position intermesh with the warp threads.

The looper, or feeder, and beating-up device are made to reciprocate so that the forward and back movements of the former shall be substantially coincident, respectively, with the back and forward movements of the latter thus: A shaft 11 is assumed to be constantly rocked through a definite range of movement by any suitable means (not shown). An arm 12 of this shaft is connected by a link 13 with a lever 14 having a toothed segment 14^a in mesh with a pinion 5^a on the looper axial portion 5. A lifter arm 15 of shaft 11 is adapted to engage and lift a lever 16 connected with an arm 9^b of the beating-up device or reed by a link 17. The rocking of shaft 11 obviously causes reciprocation of the looper or feeder and the beat-

ing-up device in the manner stated; but the operative connection is further such that there is some lost-motion of the looper or feeder with respect to the beating-up device when the former is more or less near its forward limit of motion, at which time the lifter arm is out of lifting engagement with lever 16, which then rests idly against its butt or hub, thus to give the looper opportunity to form an adequate loop for the reception of the binder-thread carrier without, also, undue lengthening of the dents of the beating-up device in order, as stated, to keep them in intermeshing relation to the warp threads even when said device is retracted. There may be a spring 18 assisting gravity to urge the lever 16 normally to the position of dwell indicated and hence the beating-up device to its back position.

By giving the beating-up device support in the frame in proximity to the fell-line B' of the fabric it can be made small in size and therefore of relatively little mass, and by further providing in mechanism comprising said device so supported and the feeder for their reciprocation together so that the forward and back movement of the feeder shall respectively, approximately begin and end when the back and beating-up movements of said device begin and end the operations of entering the filling and beating up the same to the fell may be effected very rapidly and always in proper time with each other.

The filling, coming from some extraneous supply, is formed into more or less extended loops established in the sheds as they are formed and each then taken up so that ultimately each is coextensive in length with the width of the fabric by means which includes the looper 7, in engagement with guide 7^a of which it extends; an example of this means in its preferred form will be found disclosed in my application Serial No. 310,160. Each loop is bound in by a binder thread D which becomes a supplemental, as a selvage, warp thread. Binder thread D is supplied by a shuttle or carrier in reference to which one novel and important feature of the invention is that the carrier is shot through the loop as distinguished from being carried or passed through (by "passed" I mean carried through a part of its flight by one and through the remainder by another instrumentality, with incidental transfer), the former operation making simpler mechanism and also greater rapidity of motion possible; and another novel and important feature is that since the carrier contains (by which I do not necessarily mean encloses) a binder-thread take-up tension and let-off means it maintains said thread taut and under control—more particularly, it causes this thread to pull outward on the binder-thread side of the fabric-and-warp sheet so as thereby to oppose the

tendency of the loop in being retrieved to its finally developed form when the looper recedes (dotted lines Fig. 2) to draw in and so deform said side or edge of the fabric.

The carrier for the binder thread is shown in Fig. 4, where 19 is a cylindrical case having a removable cover 20 and a fixed axial spindle 21; 22 a spring barrel forming a brake disk pressed toward the closed end of the case by a spiral spring 23 backed by a nut 24 on the spindle, a leather or other friction disk 25 being interposed between the brake disk and said end of the case; 26 a bobbin for a wound supply D' of the binder thread, the same being journaled on said nut and receiving the hub of the brake disk; 27 a spiral spring coiled about the barrel and having its ends respectively connected to the barrel and bobbin; and 28 (Fig. 3) the opening in the side of the case through which the thread is discharged. The present invention is not limited to this particular form of carrier, which will be found set forth in somewhat more detail and claimed in my copending application Serial No. 310,161, but is concerned with the fact that it contains a thread supply and also let-off tension and take-up means whereby the binder thread is kept taut, as in that moment when the loop is being taken up to its finally developed form as stated.

At the far side of the sheet from guide 7^a of the looper when retracted there is supported on the frame an upright tubular housing 29 which receives and forms a guide for the carrier. It is spaced from said side of the sheet and so located that when the looper is at the limit of its loop-forming movement the path of movement of the carrier therein will penetrate the loop formed, for which purpose this guide has its end portions in effect spaced, here by a slot 29^a in the guide, to permit the looper to pass between them. The upper end of the guide affords an abutment 29^b to which a compression spring 30 is affixed and thereon is pivoted a pawl 31 normally held by a spring 31^a in position to catch a lug 19^a on the carrier and hold the latter in the upper end of the guide with spring 30 compressed, i. e., the carrier in cocked position. The pawl has an arm 31^b by which it may be moved, against the tension of its spring, to trip the carrier, to wit, by downward pull on a link 33 connected with said arm and having an abutment 33^a. A plunger 34 is slideable vertically in the lower end of the guide; it is linked to an arm 35 of shaft 11, which arm in its downward movement engages abutment 33^a and exerts the said downward pull on link 33. Rocking of shaft 11 therefore alternately causes the plunger to rise to elevate the carrier to cocked position and descend to cause the pawl to release or trip the carrier, this latter occurring when the plunger is substantially completely depressed so that the carrier will be

shot down through the loop (then established by the looper) by spring 30. At 29° is a slot in guide 29 through which the binder thread extends.

5 The last-described mechanism will be found set forth and claimed per se in my co-pending application Serial No. 310,161. What is material here in respect to this mechanism is that it provides for shooting (as hereinbefore defined) the carrier through each loop as it is formed, as when (as in the example) the carrier is moveable back and forth and is shot through in at least one direction of its back and forth movement; and that, in another 10 aspect, given a carrier movable back and forth and normally urged in one direction and releasable means, as pawl 31, to oppose its movement as so urged, means, as the plunger and link, alternately causes the releasable 15 means to release the carrier and returns it thereto, and that when the force which normally urges the carrier in one direction is afforded by an element, as spring 30, of the mechanism this latter means causes the carrier to overcome such force in returning it.

20 Having thus fully described my invention, what I claim is:

1. A mechanism for incorporating filling as a part of the fabric of a fabric-and-warp sheet including, in combination, a frame having means to support such sheet in stretched condition, a beating-up device having support in the frame in proximity to the fabric fell and movable forward toward the fell to beat up the filling and then back from the fell, a filling feeder movable in a fixed part of the frame from one side of the sheet forward through sheds formed in the warp and back, and means operatively connecting 30 said device and feeder for reciprocation together so that the forward and back movements of the feeder shall, respectively, approximately begin and end when the back and beating-up movements of said device begin and end.

2. A mechanism for incorporating filling as a part of the fabric of a fabric-and-warp sheet including, in combination, a frame having means to support such sheet in stretched condition, a beating-up device having support in the frame in proximity to the fabric fell and movable forward toward the fell to beat up the filling and then back from the fell, a filling feeder movable from one side of the sheet forward through sheds formed in the warp and back, and means operatively connecting said device and feeder for reciprocation together so that the forward and back movements of the feeder shall, respectively, approximately begin and end when the back and beating-up movement of 40 said device begin and end, said connecting means permitting lost motion of the feeder relatively to said device when the feeder is 45 near its forward limit of motion.

3. A mechanism for incorporating filling as a part of the fabric of a fabric-and-warp sheet including, in combination, a frame having means to support such sheet in stretched condition, a dentate beating-up device fulcrumed on an axis in proximity to the sheet and substantially parallel with the fabric-fell-line and movable forward to the fell from a position where its dents extend generally lengthwise of the sheet and back to 50 said position, said dents being bent off in the direction of beating-up movement of said device and intermeshing with the warp threads when said device is in said position, a filling feeder movable forwardly across the sheet through the path of movement of 55 said device and back, and means operatively connecting said device and feeder for reciprocation together so that the forward and back movements of the feeder shall be substantially coincident, respectively, with the back and forward movements of said device.

4. In a mechanism for forming bound-in filling loops in sheds formed in the warp of a fabric-and-warp sheet, the combination of 60 supporting structure, a binder-thread carrier movable therein, means to establish a loop of filling in each shed as it is formed, and means to shoot the carrier through each loop as it is so established.

5. In a mechanism for forming bound-in filling loops in sheds formed in the warp of a fabric-and-warp sheet, the combination of 65 supporting structure, a binder-thread carrier movable therein back and forth, means to establish a loop of filling in each shed as it 70 is formed, and means to shoot the carrier in one direction of its back and forth movement through each loop as it is so established and thereupon return the carrier.

6. In a mechanism for forming bound-in filling loops in sheds formed in the warp of a fabric-and-warp sheet, the combination of 75 supporting structure, a binder-thread carrier movable therein in an upright path, means to establish a loop of filling in embracing relation to said path and in each shed as it is formed, and means to shoot the carrier through each loop as it is so established.

7. In a mechanism for forming bound-in filling loops in sheds formed in the warp of a fabric-and-warp sheet, the combination of 80 supporting structure, a binder-thread carrier movable therein back and forth in an upright path, means to establish a loop of filling in embracing relation to said path and in each shed as it is formed, and means to shoot the carrier in one direction of its back and forth movement through each loop as it is so established and thereupon return the carrier.

8. In a mechanism for forming bound-in filling loops in sheds formed in the warp of a fabric-and-warp sheet, the combination of 85 supporting structure, a binder-thread car-

rier movable therein back and forth and normally urged in one direction, releasable means to oppose movement of the carrier as so urged, means alternately to cause the latter means to release the carrier and return the carrier thereto, and means to establish a loop of filling in each shed as it is formed and in position to be penetrated by the carrier on each release thereof.

9. In a mechanism for forming bound-in filling loops in sheds formed in the warp of a fabric-and-warp sheet, the combination of supporting structure, a binder-thread carrier movable therein back and forth between definite limits, means, when the carrier is at one limit, normally urging it toward the other, releasable means to oppose movement of the carrier as so urged, means alternately to cause the second means to release the carrier and the carrier to overcome the first means and return to the second means, and means to establish a loop of filling in each shed as it is formed and in position to be penetrated by the carrier on each such release thereof.

10. A mechanism for incorporating filling as a part of the fabric of a fabric-and-warp sheet including, in combination, a frame having means to support such sheet in stretched condition, a dentate filling beating-up device fulcrumed on an axis substantially parallel with and near the fabric fell-line and movable toward such line and back, a filling feeder movable in a fixed part of the frame across the sheet through the path of movement of said device and back, and means operatively connecting said device and feeder for movement together so that the forward and back movements of the feeder shall, respectively, approximately begin and end when the back and beating-up movements of said device begin and end.

11. In combination, with supporting structure, mechanism therein for forming bound-in filling loops in sheds formed in the warp of a fabric-and-warp sheet including means to establish a filling loop in each shed as it is formed and subsequently retrieve such loop, and means to incorporate a binder thread in extending-through relation to each loop on such establishment thereof and maintain the thread taut while the loop is being retrieved.

12. A mechanism for incorporating filling as a part of the fabric of a fabric-and-warp sheet including, in combination, a frame having means to support such sheet in stretched condition, a dentate filling beating-up device fulcrumed on an axis substantially parallel with and near the fabric fell-line and movable toward such line and back, a filling feeder movable across the sheet through the path of movement of said device and back, and means operatively connecting said device and feeder for movement together so that the forward and back movements of the feeder

shall, respectively, approximately begin and end with the back and beating-up movements of said device begin and end, said connecting means permitting lost motion of the feeder relatively to said device when the feeder is near its forward limit of motion.

In testimony whereof I affix my signature.

WILLIAM S. WELLS.
